UNITED STATES PATENT OFFICE

JAMES T. ROBB, OF NEW YORK, N. Y.

LIGHTING-FIXTURE.

1,070,292.

Specification of Letters Patent. Patented Aug. 12, 1913.

Application filed January 10, 1913. Serial No. 741,224.

To all whom it may concern:

Be it known that I, JAMES T. ROBB, a subject of the King of Great Britain, and a resident of the city of New York, borough 5 of Brooklyn, in the county of Kings and State of New York, have invented a new and Improved Lighting-Fixture, of which the following is a full, clear, and exact description.

10 This invention relates generally to lighting fixtures, and is more particularly directed to types peculiarly fitted for use in hospitals or sick rooms, being intended to be positioned on the headboard of a bed. 15 The principal object of the invention is to provide a lighting fixture for the use stated which shall be easily adjusted in order to bring it to the best possible position for use, the construction and arrangement 20 being such that very simple structures are provided.

A further object of the invention, and a more specific object thereof, is the provision of clamps intended to coöperate with lamp 25 sockets, whereby the lamp carried by the socket may be advantageously positioned on the headboard of the bed.

Reference is to be had to the accompanying drawings forming a part of this specification, in which like characters of reference indicate corresponding parts in all the views, and in which—

Figure 1 is a side view of one form of fixture, one of the members of the headboard 35 of the bed being shown in section; Fig. 2 is a sectional view on the line 2—2 of Fig. 1; while Fig. 3 is a view similar to Fig. 1, and showing a second form of fixture.

Referring particularly to Figs. 1 and 2, 40 one of the members of the headboard of the bed, generally of the metal type, is designated 1, the lamp being positioned in a socket 2 which carries a shade 3, the socket being adjustable relatively to the headboard, 45 and adapted to be carried thereby through the medium of the clamp to be now described.

The clamp comprises two jaws 4—5 pivotally united at 6, a spring 7 extending 50 around the pivotal mounting and engaging the jaws, whereby they may be securely held in position on the member 1, as shown in Fig. 1. In order to prevent scratching or injury to the said member the insides of the 55 jaws are preferably provided with a relatively soft material 8, also adapted to act

as an insulator. In order to provide for easy manipulation of the jaws 4—5 each of them is preferably provided with a rearwardly extending portion 9, which portions 60 collectively form handles, so that by pressing the handles together the jaws will be released, thereby permitting the lamp to be moved to various positions on the said member 1. On the outer side of the jaw 5 is a bracket 10, having the spaced side portions 11, and between these side portions is a substantially similarly shaped member 12 having a threaded outer portion 13 with which the end of the socket 2 engages, a 70 threaded pin 14 passing through the said sides 11 and the member 12, there being a winged nut 15 on the pin so that by tightening the nut the frictional engagement between the sides 11 and member 12 will serve 75 to hold the socket and lamp in desirable position relatively to the clamp; if so desired, the adjacent faces of the said sides and member 12 may be serrated, as at 16. It will be noted that the intermediate portion of 80 the said member 12 is removed, whereby a passageway 17 is provided through which the leading-in wires 18 to the lamp are passed.

Referring particularly to Fig. 3, wherein 85 the socket 2 and shade 3 are illustrated, a different form of clamp is set forth, the jaws 4^a—5^a of which are curved, being thereby especially adapted to engage the members 1^a of headboards, which members are substantially cylindrical. The jaws are provided 90 with the handles 9 to permit their manipulation, and the spring 7 is also retained as a means of keeping the jaws in engagement with the said member 1^a. Carried by the 95 jaw 5^a is an offset 19, having a curved passageway 20 extending therein, the outer end of the offset being threaded as at 21 for engagement with the said socket 2, the passageway 20 affording convenient entrance 100 for the wires conducting current to the lamp.

The fixtures shown are simple in construction, and have been especially devised for use on the headboards of hospital beds; 105 the material of which the fixtures are made may, of course, be widely varied in order to meet different environments, the size of the parts being also capable of modification in order to adapt the fixtures to different 110 beds.

Having thus described my invention, what

I claim as new and desire to secure by Letters Patent is:—

In a device of the character described, a pair of pivotally mounted clamping jaws, 5 an upstanding member projecting from one of said jaws, a pivotally mounted lamp-supporting member arranged on said upstanding member, and means for pivotally connecting said lamp-supporting member with 10 said upstanding member, said lamp-supporting member being formed with a central

aperture extending for the full length thereof for receiving and guarding leading-in wires to said lamp, and securing means for receiving and securing a lamp in position.

In testimony whereof I have signed my name to this specification in the presence of two subscribing witnesses.

15

JAMES T. ROBB.
